UNITED STATES PATENT OFFICE.

CHARALABOS MORAITIS, OF GALVESTON, TEXAS.

SAILBOAT.

Application filed June 13, 1921. Serial No. 477,178.

To all whom it may concern:

Be it known that I, CHARALABOS MORAITIS, a citizen of the United States, residing at Galveston, in the county of Galveston and 5 State of Texas, have invented certain new and useful Improvements in Sailboats, of which the following is a specification.

This invention relates to sailing vessels, and has for one of its objects to provide an 10 improved arrangement of cables controlling the movements of the sails whereby the force of the wind alone is utilized to simultaneously shift all the sails from port to starboard or from starboard to port by merely 15 changing the course of the vessel by actuating the rudder in the usual manner.

Another object of the invention is to provide a device of this character having means whereby the operation of the rudder alone 20 causes all the sails to be simultaneously and automatically shifted.

With these and other objects in view the invention consists in certain novel features of construction as hereinafter shown and described and then specifically pointed out in 25 the claim, and in the drawings illustrative of the preferred embodiment of this invention.

Figure 1 is a side view of a single masted 30 vessel or schooner with the improved apparatus installed thereon.

Fig. 2 is a plan of the parts shown in Fig. 1 with the mast and jib sail in transverse section.

Fig. 3 is an enlarged transverse section on 35 the line 2—2 of Fig. 1 illustrating the manner of coupling the improved apparatus to the boom members.

Fig. 4 is a side elevation of the device 40 shown in Fig. 3.

Figs. 5 and 6 are enlarged details illustrating the construction of one of the cable 45 guide sheaves employed in connection with the jib operating cables.

Figs. 7 and 8 are enlarged details illustrating the construction of one of the cable 50 guide sheaves employed in connection with the boom operating cables.

Fig. 9 is a view similar to Fig. 1, with the 55 improved sail controlling means applied to a three masted vessel.

Fig. 10 is a side elevation of the parts shown in Fig. 9 with the jib sail and the masts in transverse section.

The improved apparatus may be adapted 60 without material structural change to sail

boats or yachts of one or more masts and one or more jib sails, or to larger vessels having two or more masts and one or more jib sails, and it is not desired to limit the invention to any specific vessels with any particular number of masts, but for the purpose of illustration the improved sail controlling apparatus is shown applied to a one masted sail boat or schooner, having one jib, and 65 also to a three masted schooner type, having one jib.

In Figs. 1 and 2 of the drawings the hull of the vessel is indicated at 10, the deck at 11, the mast at 12, the jib boom at 13, the main boom at 14, the main sheet at 14', the jib sail at 15, the main sail at 16, and the rudder at 17 having the usual steering wheel at 18.

In Figs. 9 and 10 the corresponding parts 75 are designated by the same reference character except that the foremast is represented at 19, the main mast at 20, the main sheet at 20', the mizzen mast at 21, the foremast boom at 22, with its main sheet at 22', the main mast boom at 23, the mizzen mast boom at 24, with its main sheet at 24', the foresail at 25, the main sail at 26 and the "spanker" at 27, these parts also being arranged in the usual manner. 85

The improved apparatus includes double cable guide sheaves represented as a whole at 28 and attached to the deck 11 or other part near each rail and near the bow, or slightly forward of the line of the mast 12 90 or 19, as the case may be. Twin cable guide sheaves 29 and 30 are attached to the deck 11 or other part of the vessel some distance astern of the mast 12 and the other masts 19 and 20 and 21 as shown. Attached to 95 each of the booms 14—22—23 and 24 is a sheave supporting device illustrated more fully in Figs. 3 and 4 and each comprising clamp members 31 and 32 hingedly united at 33 and clamped around the booms by a bolt 100 34. The clamp members are provided respectively with cable guide sheaves 35—36 as shown.

Suitable cleat devices 37 and 37' are also attached to the deck 11, or other part, as 105 shown.

Attached to the jib sail 15 at the point where the usual jib sheet is connected are two sheets or cables 38 and 39.

The cable 38 is conducted around one of 110 the sheaves in one of the blocks 28, thence across the deck and around one of the

sheaves in the other block 28, thence along the deck and around one of the sheaves in the block 30, thence around the sheave 36 on the boom 14, thence around the other 5 sheave of the block 30 and thence to the cleat 37.

The other cable 39 is conducted around one of the sheaves of the other block 28, thence around the other sheave in the other 10 block 28 and thence along the deck and around the sheaves in the corresponding sheave 29 and guide sheave 35 on the boom 14 at the other side of the vessel, as shown, and finally attached to the cleat 37.

15 By this arrangement the cables may be adjusted to allow the sails 15 and 16 any desired amount of "play" according to the velocity and direction of the wind.

When employed on a two or more masted 20 vessel, the cables 38 and 39 are simply extended in the same manner through a series of the sheaves, as shown in Figs. 9 and 10.

By this arrangement when the steersman 25 desires to tack or turn about, he shifts the rudder to bring the vessel into the wind, and when the latter has turned far enough to expose the opposite sides of the sails to the wind, the pressure of the wind on the main sails will throw them over and carry the jib 30 sail with them through the action of the coupling cables 38 and 39, as will be obvious, and without the necessity for manipulating them separately, and thus automatically set

the sails to correspond with the change of direction.

35

The device is simple in construction, can be readily applied to vessels of various sizes and to vessels having various arrangement and number of sails.

The preferred embodiment of the invention is disclosed in the drawings and set forth in the specification, but it will be understood that any modifications within the scope of the claimed invention may be made in the construction without departing from the 40 45 principle of the invention or sacrificing any of its advantages.

What is claimed is:—

In a sailing vessel including a jib sail and masts carrying booms and mainsails, of a 50 plurality of guide sheaves attached to the vessel along its opposite sides and spaced to correspond to the mainsails, a guide sheave attached to each of said booms, cables attached at one end to said 55 jib sail, means for guiding said cables from the jib sail respectively to the foremost guide sheaves of the vessel at opposite sides thereof, said cables being thence carried alternately around the sheaves of 60 the vessel and the sheaves of the booms, whereby the shifting of the mainsails will correspondingly shift the jib sail.

In testimony whereof I affix my signature hereto.

CHARALABOS MORAITIS.
